UNITED STATES PATENT OFFICE.

HENRY M. WEAVER, OF MANSFIELD, OHIO.

CASH AND PACKAGE CARRIER.

SPECIFICATION forming part of Letters Patent No. 367,874, dated August 9, 1887.

Application filed February 26, 1887. Serial No. 222,970. (No model.)

To all whom it may concern:

Be it known that I, HENRY M. WEAVER, of Mansfield, in the county of Richland and State of Ohio, have invented certain new and useful Improvements in Cash and Package Carriers; and I do hereby declare the following to be a full, clear, and exact description of the invention, such as will enable others skilled in the art to which it appertains to make and use the same.

My invention relates to an improvement in cash and package carriers, the object being to construct a simple, reliable, and convenient device by which the basket or receptacle containing the article to be transported may be raised and attached to the conveying-car or detached and lowered therefrom quickly at a proper station or terminal point of the track on which the car travels.

20 A further object is to provide a means of attachment for a package-receptacle that will be automatically detachable from the conveying-car at terminal points on the track or line wire upon which the car moves.

25 A further object is to provide a latching device that will readily connect the package-receptacle of a cash or package carrying system and permit its instant release at a station, and that will be applicable to systems employing 30 one or more tracks.

35 A further object of my invention is to provide a car for a cash and package carrying system that will afford journalized support for its wheels in a manner to reduce friction at these revoluble bearing-points.

With these objects in view my invention consists in certain features of construction and combinations of parts that will be hereinafter described, and pointed out in the claims.

40 Referring to the drawings making a part of this specification, Figure 1 is a side elevation of a two track cash-carrier system adapted to use my improved car and latching device. Fig. 2 represents a terminal station of a single-track cash and package carrier system that embodies features of my invention to adapt it to utilize my latching device. Fig. 3 is a side elevation of the automatic latching device that effects a connection of the cash and package 45 receptacle with the conveying-car. Fig. 4 is a view of the latching device shown in Fig. 3,

with a different adjustment of parts shown. Fig. 5 is a side elevation of a modified form of the latching device. Figs. 6, 7, 8, and 9 are views of details of the latching device. 55 Fig. 10 is an end elevation of the conveyer-car in position upon a double track.

The subjects of my present invention being essentially embraced in the car and latching device that connects the receptacle with this 60 car, I do not limit the use of these novel devices to any particular system of package-conveyance, as it is applicable, by slight modifications of construction, to a single or double track, on which either gravity or springs are 65 used as a means of propelling the car.

I will first describe the conveying-car in connection with a double-track system such as is employed by Samuel Barr, and for which a patent was allowed January 20, 1887. 70

The conveying-car E is shown in place upon the double track of wire or wire rope in Fig. 1. It is constructed with a horizontal bar, E', of proper length, preferably made of pipe of suitable diameter. The ends E' are attached 75 by screw-threads to the ends of the bar E', and the portions E' are each provided with a vertical extension, a, cast integral upon their sides, as shown in Fig. 10. The parallel vertical plates a' are rigidly attached at the top 80 ends of the pieces a upon the laterally-extended spacing-bosses a⁴, which are integrally formed on the pieces a at their upper ends. The lower ends of the attached pieces a' are secured to the sides of the enlarged ends E' of 85 the bar E'. It will be noticed that the relative position of the mated vertical pieces a' a permits a space to intervene between their opposed surfaces. The sheave-wheels a² a³ are made of such proportioned diameter and thickness as to allow them to be pivoted to rotate between the pieces a' a, the sustaining-pintles being integral or rigidly fixed in the wheel and inserted at 90 in the plates, as shown in Fig. 1. The diameter of the sheaves a² a³ will 95 permit their grooved edges to closely approach each other and to receive the wires F F' in the grooves of their peripheries, the upper wheels resting upon the wire F, the lower wheels having the wire F' resting in their channeled 100 edges. The bosses a⁴, that are placed at the top of the connected standards a' a', are prefer-

ably rounded in their bodies to present a curved top surface, and may be covered with elastic material to act as a cushion.

Upon the horizontal bar E' of the conveying-car E, near its center considered lengthwise, the depending bracket-arm G is located, its perforated boss being made to neatly fit the body of the bar. This bracket is composed of two vertically-descending arms, G', that are parallel a portion of their length and have their lower terminations curved outwardly or in opposed directions in the same vertical plane. Upon the hanger A, at the point e, immediately above the collar formed on the thimble c', the laterally-extended arm B is secured, a boss, c', being provided on its end to embrace the vertical hanger and be secured thereto at a desired point by the set-screw c'.

Referring to the track-supporting device, (see Fig. 1,) the arm B is made of proper length to extend above the assigned position occupied by the conveying-car E. This arm is bifurcated at a point near the boss c', the parallel separated limbs of the same having a space intervening of sufficient width to receive the sheave-wheel-frame supports of the conveying-car E and permit these parts to freely move a required distance between them. Upon the forwardly-extended end of the lever A' the spring S is fixed by its foot e, and extends above the line-wires F F' in a position to engage the spacing-bosses a' of the conveying-car E. The spring S is curved, as shown in Fig. 1, the front end being bent upwardly to permit the spacing-boss a' to impinge upon its lower surface at e' and lift the spring by the momentum of the approaching conveying-car when it is sent from an opposite terminal of the line. The curvature given the spring S is such that the portion of the body at the point e' will act as a buffer to properly check the carriage, which will ultimately rest at the point e', near the shoulder e'', formed on the spring S. (See Fig. 1.)

Near the securing-flange A' of the hanger A the laterally-projecting bracket C is mounted and secured in place upon the body of the hanger. The bracket-arm C is made to extend such a proportionate distance from the hanger A that its outer end will be about in a vertical line with the outer extremity of the forked arm B, that is located below it on the same hanger A. Several spaced perforations 1 2 3 4, are made in the side wall of the arm C, these holes being provided to receive the pintle of a grooved pulley, D', which is located between the parallel jaws of the forked end of the lever C, that is slotted to produce two limbs of sufficient length to accommodate the pulley D', as just stated.

In Figs. 1 and 10 the parallel depending rods D are shown. The upper ends of these rods are rigidly connected by the cross-bar D', their length being such that the lower ends, which are bent into hooks D'', will rest opposite the bar E' upon each side of the same, when these rods are elevated, as shown in

Fig. 1, with their connecting cross-bar D' resting against the lower surface of the plate-spring D', which is secured in place upon the under side of the bracket-arm C, its free end being slotted to allow the cord D' to be extended from the center of the cross-bar D' upwardly, and lie in the groove of the pulley D', this cord being made of sufficient length to extend downwardly to a point convenient to be grasped by a clerk or other operator.

The parallel arms of the bracket B are each provided with a series of spaced holes that are furnished with thimbles 7 8 9, &c., that are preferably made of hard wood, these being centrally perforated through their length to receive the vertical rods D and support them in position to allow these rods to move freely in the thimbles, which act as guides for the rods D, when they are elevated or depressed. The distance between the thimbles 7 8 9 is the same as the space between the holes 1 2 3, &c., that are made in the slotted ends of the arm C. This provision is made to permit the hooks D to be given a change of position to accommodate a longer or shorter arm on the horizontal lever A', the variation of length in the construction of the lever A' being provided to suit the wants of a long or short line-wire that extends to stations that vary in distance from the cashier's stand.

One of the most essential provisions of a well-constructed cash and package transporting apparatus consists in a ready and convenient means of connecting and disconnecting the receptacle in which the cash or goods is deposited with or from the conveying-car, and also to provide for the lowering from or elevation to this conveying-car, which is adapted to move upon the track that rests in a plane a proper distance above the counter to avoid impediments to free travel of the car.

I will now proceed to describe my improved latching device that will automatically effect a connection or release of the receptacle with or from a conveying-car, and in conjunction with other simple devices permit the lowering of the basket or package-receptacle from the conveyer-car to the counter or the hand of the operator.

In Figs. 3, 4, 5, and 6, H represents a frame of metal. It is a flat plate having a slot, f, cut in its center, the upper edges of this slot being curved in opposite directions to form the diverging limbs f' f'', which are of equal width and thickness. At the base of the limbs f' f'' the laterally-extended integral ears i are projected from each side of the frame H, the lower edges, i', of these ears being scalloped to form hooks that are intended to engage the bent lower ends of the rods D when in proper position to do so. The lower portion of the frame H is widened, and this portion of the body of the frame has a slot, f'', made through it to receive the spiral spring f'', the thickness of the material permitting this spring to rest in the slot and not project beyond the line of its sides.

To the lower end of the frame H two rods,

h, are extended diagonally downward to connect the frame rigidly with the body of a basket or other suitable cash or package receptacle.

5 The hook-plates *H'* are made in the form shown in Figs. 3, 4, and 9, the upper part being made in shape as shown, with an inclined side edge that is widened at the point *f*⁴ to form a hook, which is adapted to engage a 10 transverse pin, *k*, that is rigidly secured in the parallel portions of the forked depending bracket *G*, which is mounted on the bar *E'* of the conveying-car *E*. The lower portions of the hook-plates *H'* are curved slightly to the 15 rear of the hooks *f*⁴, and are extended at the point *f*⁶ laterally to form a cover for the spring-box *f*³ that is cut in the frame *H*. It should be stated that the two hook-plates *H'* are duplicates of each other in form, and are pivotally secured at the point *f*² to the frame *H* 20 upon opposite sides of this frame.

At the end *f*⁷ of the plates *H'* a block is riveted to the inner faces of the plates, this block *f*⁷ being made of such proportionate 25 size as to work freely in the slot or spring-box *f*³, and thus receive the end-thrust of the spiral-spring *f*⁸, which is located in the box *f*³.

An ear is made to extend from the frame-plate *H* at its lower corner that is nearest to 30 the block *f*⁷, to afford a support to the mated locking-bars *J*. These bars are connected integrally at the heel *t*, and being given a position on each side of the frame *H* are pivoted at the point *g*⁹ to this frame to vibrate thereon.

35 The upper portions of the locking-bars *J* are made to extend toward the center slot, *f*, in the frame *H*, so that the ends *g*⁹ of these bars will be in contact with the ends of the hooks *f*⁴ of the plates *H'* when the lower edges of the lateral limbs *J*² of the bars *J* are in sliding contact with the upper edge of the parts *H*³ of the hook-plates *H'* that form a cover for the spring-box *f*³, and it will be seen that this contact of parts will take place when the hooks *f*⁴ of the 40 hook-plates *H'* are extended across the vertical slot *f* of the frame *H* to engage the cross-bolt *k*, which is fixed in the sides of the depending arms of the bracket *G* that is connected to the bar *E'* of the conveying-car *E*.

45 The free ends of the lateral extensions *J*' of the parallel locking-bars *J* are notched to form offset or shouldered catches *g*² thereon. The relative length of the adjacent lower parts of the hook-plates *H'* and locking-bars *J* is such that the notches *g*² will engage the shoulders *f*⁷ of the portions *H*³ when the hooks *f*⁴ are made to recede sufficiently to cause their inclined edges to line with the inner curved edges of the frame *H*, (shown in Fig. 4 of the drawings.)

50 as from the construction and point of pivotal connection of the bars *J* it is apparent that the entire weight of these bars will operate to cause their free ends *g*⁹ to bear upon the points of the hooks *f*⁴, and continue to have such contact when the bars and hooks are in the position shown in Fig. 4, as already alluded to.

55 In Fig. 1 the position of the automatic latch-

ing-frame *H* and its connected parts in relation to the bars of the forked bracket *G* is shown, the hooks *D*⁵ of the rods *D* being in engagement with the hooks *i* of the latching-frame. In this figure the cash or package receptacle is elevated by the draft of the cord *D'* to suspend it in the position shown in Fig. 3. If the elevation is continued, which causes 75 the boss *G* to impinge upon the inclined edges of the latch-plates *H'*, these plates will then recede and the hooks *f*⁴ be disconnected from their engagement with the cross-bolt *k*, so as to release the basket from the conveying-car 80 *E*. The basket or cash-receptacle is now supported upon the hook ends of the rods *D*, and can be lowered to the hand of an operator at a clerk's station by the cord *D'*.

The abutment of the hooks *f*⁴ upon the sides 85 of the boss *G* to throw them in the position shown in Fig. 4 will cause the locking-bars *J* to assume the position shown in this figure. The ends *g*⁹ of the extension *J*' will have a locking engagement with the ends *f*⁷ of the 90 plates *H*³, and thus hold the spring *f*³ compressed, the hooks *f*⁴ being in secured adjustment. The basket can remain in this position till the clerk or operator wishes to inspect its contents. The act of lowering the basket, as 95 above stated, will cause the lower edge of the upright limbs of the bars *J* to strike the cross-bolt *k* of the bracket *G*², and by this contact the bars will be thrown back and the locks *g*² of the lower limbs, *J*', of these bars *J* will be 100 detached from engagement with the ends *f*⁷ of the hook-plates *H'*. The bars *J* and hook-plates *H* will then assume the position shown in Fig. 3 and the latching device be automatically adjusted to re-engage the bolt *K* of the 105 bracket *G*, when the basket is again elevated to connect it to the conveying-car. When cash or packages are to be forwarded from a clerk's station to a cashier's stand or a bundle-table, the articles being deposited in the basket, it is elevated and made fast to the car as just described, the handle *b*³, that is connected to the rear end of the horizontal lever *A*², is grasped and the rear end of the lever *A*² depressed by its aid. The vibration of the lever *A*² will cause it to assume a vertical position, in consequence of 110 which the attached line-wires *F* *F'* will be spread apart forcibly. These by their divergence will act upon the wheels *a*² *a*³, and give a forward impetus to the conveying-car and 115 its attached cash and package receptacle, the detent spring *S*, by its change of position from a horizontal to a vertical plane, being removed from engagement with the spacing-boss *a*⁴ of the conveying-car simultaneously with the oscillation of the lever *A*² and the consequent progressive impact of the line-wires *F* *F'* upon 120 the wheels of the car *E*.

In Fig. 5 a modified form of latching device is shown. It is constructed similar to the automatic latch shown in Fig. 3, with the exception that the bars *J* are dispensed with and a horizontal forked latch, *T*, is substituted. This latch is made to engage the plates *H*³ by means 130

and the ends of the locking-notches g^2 on the free ends of the latch which is pivoted to rest horizontally and bear upwardly against the lower edges of the latch-plates II^3 to engage the shoulders of these plates when the latches are forced into a proper position to permit this locking contact of parts. The rearwardly-projecting end k' of the latch T is enlarged to form a weight sufficient to cause this forked latch T to engage to the ends of the latch-plates II^3 by their gravity. This latching device is not strictly automatic, as the release of the lock, which is effected by the latch T , must be executed by the hand of the operator. When a return of the cash-carriage is to be made from the cashier's stand to any clerk's station, it is effected by a depression of the rear end of the lever A^2 , a proper handle being affixed thereto for convenience in operation of the device. The cashier's stand being elevated a suitable height, it is not necessary to furnish the depending handle, which is provided for a clerk's station.

In Fig. 2 is shown a terminal station of a single-wire-track system, which is made to receive my improved car and my improved receptacle-lowering device, the automatic latching-hooks for connecting the car and package-receptacle being as well adapted for use in this plan of construction as in the double-track system shown in Fig. 1. J is the depending hanger upon which the apparatus is suspended. I is a tension-screw to adjust the wire S . The horizontal arms A are affixed rigidly upon opposite sides of the vertical hanger J . Grooved pulleys E E are rotatively secured at each end of the arms A A , and to the ends of these arms, above the wire S , tubular sockets C D are secured to project downwardly a short distance above the track-wire. Two cords or wire ropes, o o , of proper pliability, are attached to the hooks G at their ends L L , and are made to pass through the sockets C D , thence rearwardly to rest upon the grooved wheels E E and descend together, uniting in a handle, H , to which they are attached. It will be noticed that the elevation of the hooks G G , which are joined by the bar p , will cause the upper ends, L , of the straight shanks of these hooks to enter the sockets C D when the handle H is pulled down, and in this way hold in secured position the hooks G G for the reception of the ears i i on the frame II of the latching device shown in Figs. 3 and 4 of the drawings.

The car B shown in Fig. 2 is provided with two wheels, 1 2 , which are attached to vertical standards affixed to the horizontal bar O . The wheels are each provided with rigid journal-shafts, as is the case with the four-wheeled car. The other features of the car are identical with the details of construction of the car shown in Figs. 1 and 10, and it will be evident from the foregoing description that the same efficiency of action is attained in the car and other adjunctive features of the single-track system as is derived by use of a double-track mechanism.

I do not wish to limit myself to the exact features of construction shown in the illustration of my improved latching devices, as they may be modified. For instance, a single latch-plate, II , may be employed in lieu of the parallel pair that are shown in Figs. 3, 4, and 5, and, in like manner, a single locking-bar, J , may be employed in place of two, as shown in these figures. A flat plate-spring may be substituted for a spiral spring, f^3 , in the latching-device. Again, the pulley D^2 may be attached directly to the ceiling of the room by a bracket without using the arm C shown in Fig. 1 to support it.

Having fully described my invention, what I claim as new, and desire to secure by Letters Patent, is—

1. In a cash and package carrier, the combination, with a hanger, a lateral arm on the hanger, and a track beneath this arm, of a car, an automatic latching device for connecting the receptacle to the car, and two depending rods provided with hooks to engage two projecting ears formed on the frame of the latch-device, substantially as set forth. 85
2. In a cash and package carrier, the combination, with a hanger, a lateral arm on the hanger, and a track beneath this arm, of a wheeled car, latching device for connecting the receptacle to the car, two depending rods having hooks to engage the ears on the latch-device, and a flexible cord adapted to raise and lower the rods, substantially as set forth. 95
3. In a cash and package carrier, the combination, with a hanger, a lateral arm on the hanger, a spring that prevents recoil of the car, and a track beneath this arm, of a wheeled car, a latching device to engage the car, two parallel depending rods having hooks on their lower ends to engage ears on the latch-frame, a flexible cord or rope, and means to support it and allow its easy movement to elevate and depress the rods when a package-receptacle is suspended thereon, substantially as set forth. 105
4. In an automatic latching device for a cash and package carrier, the combination, with a center slotted frame having oppositely-extended ears, of a latch-hook, a spring to engage the hook and force it across the line of the vertical slot in the frame, and a pivoted locking-bar adapted to engage the heel of the latch-hook and hold it in open adjustment, substantially as set forth. 115
5. In a cash and package carrier, the combination, with a conveying-car having grooved wheels and a depending forked bracket carrying a cross-pin, of a latching-frame attached to the package-receptacle adapted to engage the cross-pin, substantially as set forth. 125
6. In a cash and package carrier, the combination of a conveying-carriage provided with grooved wheels having fixed axles made to rotate in bearings formed in parallel vertical brackets, the brackets being connected at their upper ends with rounded spacing-bosses that are adapted to collide with a buffer-spring. 130

when the car approaches the terminal point of the track, substantially as set forth.

7. In a cash and package carrier, the combination, with the latch-frame H, pivoted latch H', spring f⁸, and locking-bar J, of a wheeled conveyer-car that is provided with a depending bracket, G, that has bifurcated oppositely curved arms G', and a cross-pin, k, which is adapted to engage the latch-hook of the latch-

ing-frame and thus connect the car and package-receptacle, substantially as set forth.

In testimony whereof I have signed this specification in the presence of two subscribing witnesses.

HENRY M. WEAVER.
